ELECTROMAGNETIC LOCK FOR X-RAY APPARATUS

Robert J. Stava, University Heights, and Walter G. Reininger, Cleveland, Ohio, assignors to Picker X-Ray Corporation, Waite Manufacturing Division, Inc., Cleveland, Ohio, a corporation of Ohio

Application June 3, 1950, Serial No. 166,016

20 Claims. (Cl. 188—165)

1

This invention relates to X-ray apparatus and more particularly to a manner and means of controlling and arresting the inherent movement of relatively movable members of the apparatus.

X-ray apparatus may be employed for various diagnostic and treatment purposes, and the manner of employment involves various techniques depending upon the type of examination or treatment, such as radiography or fluoroscopy. Accordingly, this type of apparatus must usually be constructed so that the various operable members of the apparatus can be moved to a plurality of positions individually or in combination in accordance with the technique employed. Operation of an apparatus of this type which requires many relative movements also inherently requires means for arresting such movements. This is particularly true in the operation of X-ray apparatus where many of the final settings of movable members, such as the X-ray tube or fluoroscopic screen, require accuracy and prohibition against misalignment.

Heretofore, various types of mechanical locks in the form of screw or toggle mechanisms have been utilized for this purpose in X-ray apparatus. Such mechanical locks, however, are widely separated and require periodic adjustment and alignment, thus making operation of the apparatus inconvenient and burdensome for the operator.

Accordingly, it is an object of this invention to provide a magnetic type lock for X-ray apparatus which may be conveniently located for operation and which requires a minimum of adjustment and maintenance.

Another object of this invention is to provide an electro-magnetic lock for X-ray type apparatus having a plurality of movable elements and, which lock is self-adjusting and subject to remote control.

A further object of this invention is to provide an X-ray type apparatus having a plurality of relatively movable members and having a magnetic type lock for arresting each of the members individually, or in combination.

Briefly, in accordance with this invention an electro-magnetic type lock is provided which embodies a magnetic core surrounded by an energizing coil adapted to be carried by a supporting member and having a flexible member adjacent one face of the core which frictionally engages another member of the apparatus upon energization of the magnet coil whereupon the magnet is attracted to the other member in locking relation. Various combinations of the elec-

2

tro-magnetic type locks are distributed in operative relation throughout the X-ray apparatus in association with the various relatively movable members and have individual or combined energizing circuits including controlling switches, whereupon certain members of the apparatus may be arrested in movement individually or together with certain other movable elements in predetermined relation.

10 These and other objects and advantages of the invention will be further understood from the following description when considered in connection with the accompanying drawings and as pointed out in the appended claims.

Fig. 35 is a front view of the carriage of Fig. 34 showing the dial for indicating the angular position of the auxiliary X-ray tube relative to the stand;

Fig. 36 is a side elevation of the X-ray apparatus showing the bucky radiograph assembly in relation to the X-ray tube stand and fluoroscopic unit;

Fig. 37 is a sectional view taken along the lines 37-37 in Fig. 36, showing the various positions

of the film cassette tray relative to the bucky carriage and the associated electro-magnetic lock;

Fig. 38 is a top view of the table showing in dotted lines the various positions of the film cassette relative to table;

Fig. 39 is an enlarged sectional view of the bucky assembly electro-magnetic lock; and

Fig. 40 is an energizing circuit diagram for individually controlling the bucky assembly electromagnetic lock.

The electro-magnetic lock of this invention is shown in detail in Figs. 1 to 6. The remaining figures of the drawings illustrate by way of example, various applications of such an electro-magnetic lock in a particular type of tiltable X-ray apparatus.

Referring to Fig. 1, a hexagonally shaped electromagnet 1 is mounted on a supporting member 6. The magnet 1 may be made of soft iron or other suitable low residual magnetic material and is hexagonally shaped on the exterior, as shown in Fig. 3, to prevent rotation of the magnet relative to the supporting member 6. The magnet 1

has an interior concentric slot for receiving an energizing coil 2. This construction results in a magnet having an inner central core 3 surrounded by a coil, both of which are enclosed by the outer leg or perimeter 4 of the magnet 1. A magnetically susceptible member 5 of iron, steel, or like material is positioned adjacent the core face of the magnet 3.

A source of electrical energy, not shown, may be connected to the leads 7 to energize the coil and polarize the magnet. The path of the magnetic flux travels towards the core face through the central core 3 and back through the perimeter or outer leg 4 of the magnet. Accordingly, when the magnetically susceptible member 5 is positioned adjacent the core face of the magnet 1, the magnetic flux from the magnet traverses the adjacent regions of the member 5 making this member magnetically reverse in polarity to the adjacent pole faces of the magnet. The result is that the member 5 acts as an armature and is magnetically attracted to the magnet or vice versa, thus forming a closed magnetic path for the flux traveling from the central core outwardly through the member 5 and back through the perimeter 4 of the magnet.

In practice, the member 5 may be a stationary track and the magnet 1 may be carried on an adjacent movable member which is guided along the track so that when the magnet is energized, the attraction between the track and the magnet acts to arrest the movement of the movable member 6 relative to the stationary track 5.

In its preferred form, the electro-magnetic lock to be hereinafter more fully described in connection with a tilt-table type X-ray apparatus, should be small enough and have sufficient power to provide positive magnetic locking action between the stationary and movable members of the apparatus. This type of action may be accomplished

by constructing an electro-magnetic lock having locking forces of between 16 and 30 pounds against sliding motion. In order to further enhance the arresting power of the magnet and to overcome the slight amount of friction developed by residual magnetism, a cover 35 of flexible material, such as neoprene, is provided for the magnet which projects approximately $\frac{1}{4}$ of an inch beyond the face of the core. The neoprene face is preferably made in the form of a cylinder whose walls insulate the coil from the

core and whose face is the braking or arresting surface of the magnet. Since the neoprene has a greater co-efficient of friction to steel than does steel to steel, the effort required to move a lock assembly is increased. Furthermore, the elasticity of the neoprene face results in a mushroom-type action which has a greater gripping power so that when the magnet is de-energized the neoprene, in returning to its original state, acts as a spring and lifts the magnet free of the track or armature, thereby eliminating any undesirable effects of residual magnetism in the magnet core.

In the embodiment shown in Figs. 1 to 4, the magnet 1 is provided with annular grooves 8 on its external diameter for keying the magnet 1 to the supporting member 6. The supporting member 6 may be punched or otherwise provided with a hexagon hole as shown in Fig. 4 and the magnet 1 is inserted with snap rings 9 in the annular grooves immediately adjacent the supporting member 6. The spaces between the annular grooves 8 are sufficiently large to allow the magnet 1 to float between the snap rings 9 and thereby be self-aligning. With this arrangement, the magnet 1 is attracted to the armature or track 5 when the coil is energized. However, it is apparent that other forms of construction may be utilized to carry out the same principle of operation. For example, the magnet 1 may be fixedly retained on the supporting member 6 and the armature or track arranged to be movable.

Other embodiments of the electro-magnetic lock structure are shown in Figs. 5 and 6. In Fig. 5, the magnet 1 is shown fixedly mounted on the supporting member 6, and in Fig. 6, the magnet 1 is shown loosely carried adjacent the supporting member 6 against the action of a spring or resilient member.

The principle of the electro-magnetic lock is shown in the remaining drawings applied to a tilt-table type X-ray apparatus, carrying out the techniques of radiography and fluoroscopy. Referring to Figs. 6, 7, and 8 a frame 11 supports a table 12 for tiltable movement relative to the frame. The table 12 is provided with a longitudinal track as shown by the dotted lines 13. An X-ray tube head 14 including a shutter mechanism 15 and a fluoroscopic screen unit 16 having a spot-film device 17 are mounted on a supporting column 18 which is movably supported in a carriage 19 for longitudinal or crosswise positioning relative to the table 12.

The carriage 19 is mounted for movement longitudinal of the table 12 on anti-friction rollers 20 which are carried in the track 13. The carriage 19 is also provided with a track 21 which extends within the carriage frame in a direction crosswise of the table 12. The supporting column 18 is also mounted on anti-friction rollers 22 for movement in the carriage track 21 crosswise on the table 12.

In their preferred form, each of the tracks 13 on the table and 21 in the carriage are provided with a magnetically susceptible member throughout their entire distance. The carriage 19 carries a magnet 23 of the type previously described which magnet may be remotely energized and controlled to lock against the track 13 and thereby arrest the longitudinal movement of the carriage relative to the table 12. The supporting column 18 is also provided with a magnet 24 adapted upon energization to coact in magnetic locking relation with the carriage track 21 to arrest crosswise movement of the supporting column 18 relative to the table 12.

The spot film device 17, which is carried within the fluoroscopic unit 16 above the table 12 is used by a radiologist to fluoroscope a patient on the table so that the moment the radiologist observes pathology of interest, he may quickly record it on film. For example, in the investigation of a stomach for ulcers, the patient is usually required to swallow barium meal which is radio opaque and as the barium descends into the stomach, the radiologist may palpitate the stomach in order to force the barium into the crater of the ulcer. The moment he visualizes this condition, he brings the film over very rapidly and makes a record. These films are usually small and as the barium descends into the stomach it is not possible to radiograph the entire tract on the spot film device. Furthermore, films taken with the spot film device are not of the quality that can be attained by means of a bucky radiograph and it may be necessary to transfer the center of pathology from the fluorescent screen to a radiographic tube on an auxiliary tube stand. In the case of fluoroscopy and spot-film operations, it is not necessary to place the patient in the exact center of the table. However, if a bucky radiograph is to be made, the patient must be centered on the table over the bucky diaphragm and associated film cassette. Accordingly, the carriage 19 is provided with electro-magnetic locks having at least two types of action as will be hereinafter more fully described.

Referring to Figs. 12 and 14, the crosswise electro-magnetic lock 24 is shown connected through a mechanical centering switch 25 and a line switch 27 to a source of electrical energy. The centering switch 25 is spring operated and is mounted on the X-ray tube head 14 to cooperate with a notch 28 which is centrally located on the carriage 19 relative to the sides of the table 12 so that when the supporting column 18 and the associated tube head 14 are centrally positioned crosswise in the table 12, the spring operated switch arm 26 is free to move into the notch 28 and close the energizing circuit to the crosswise electro-magnetic lock 24, thereby arresting further crosswise motion of the supporting column 18 relative to the table.

In accordance with the above described radiographic and fluoroscopic techniques, other forms of individual and combined action of the longitudinal and crosswise electro-magnetic locks may be desirable. For example, it may be desirable to have both the longitudinal and crosswise electro-magnetic locks operate simultaneously and instantaneously upon operating the control. On the other hand, the technique may require that neither of these locks be energized until the X-ray tube head and associated apparatus is centered on the table 12. Fig. 17 illustrates a control circuit which may be adapted for either of these types of operation, depending upon the positioning of a switch 29.

In this circuit, the longitudinal and crosswise electro-magnetic locks 23 and 24 are shown connected in parallel through a single pole, double-throw switch 29 to a source of electrical energy so that when the switch 29 is in the right-hand position, both of the electro-magnetic locks are simultaneously energized regardless of the relative positions of the controlled members. The other side of the switch 29 is connected through the centering switch 25 to the parallel connected electro-magnetic locks, so that when the switch 29 is thrown to the left-hand position, neither of the electro-magnetic locks are energized until

the X-ray tube head is centrally positioned crosswise of the table 12. The technique of locking both electro-magnetic locks simultaneously regardless of the position of the controlled members would normally be used just before making an exposure with the spot film device, while the technique of with-holding the locking of these locks until the tube head is centrally positioned crosswise of the table would be used when transferring to a radiographic exposure. In the latter case, with the carriage 19 locked in the exact center of the table, the patient may be moved on the table until the part of which a bucky radiograph is to be made is centered in the radiograph screen. An auxiliary tube stand 10, shown in Fig. 31, may then be brought into place and centered with the fluoroscopic unit by means of either a mechanical or optical centering device not forming part of this invention and therefore not shown. After the auxiliary tube stand is thus centered, the carriage 19 may be unlocked and moved out of the way as shown by the dotted lines 18A in Fig. 7.

One of the significant features of arresting the various motions of an X-ray apparatus by an electro-magnetic type lock is the variety of possible controls that may be accomplished with any given individual or combination of electro-magnetic locks. Thus, in addition to the several embodiments of control circuits shown in Figs. 14 and 17, it may be desirable in the apparatus shown to provide the type of control associated with the circuit shown in Fig. 18. The switch 30 may be in the form of a double pole, double throw switch with a neutral position or it may be a push button type switch having a like number of poles and positions. The control technique resulting from operation of the switch 30 in Fig. 18 is such that when the switch 30 is in the lower position and engaging the lower respective contact members 31 and 32, the longitudinal electro-magnetic lock 23 is immediately energized to arrest the longitudinal motion of the carriage 19 relative to the table 12, while the crosswise lock 24 is not energized until the X-ray tube head 14 is centrally positioned crosswise on the table 12, whereupon the centering switch 25 operates to close the energizing circuit to the crosswise electro-magnetic lock 24. When the switch 30 is in the upper position to engage the contact members 33 and 34, the centering switch 25 is excluded from the energizing circuit and both the longitudinal and crosswise electro-magnetic locks are immediately energized to simultaneously arrest both the longitudinal and crosswise movements of the supporting column 18 relative to the table 12.

As previously noted, the illustrated X-ray apparatus is a tilt-table type apparatus which may be tilted to intermediate angular or vertical positions relative to the supporting frame 11. When the table 12 is in the horizontal position shown in Fig. 7, the only forces of resistance to longitudinal motion of the supporting column 18 are the frictional forces between the rollers 20 and the track 13. However, when the table 12 is vertically positioned, as shown in Fig. 15, the weight of the supporting column 18 acts to aid downward motion and to restrain vertical motion of the column 19 along the longitudinal track. Accordingly, as shown in Fig. 15, in dotted lines a counterweight arrangement is provided to balance the vertical motion of the supporting column 19. The counterweight arrangement may be of any suitable form and may comprise a

closed belt or cable 40 interconnecting the supporting column 18 with the weight 41. The cable 40 may be supported within the table 12 by means of pulleys 42.

Referring now to Figs. 20, 21, 22, and 23, the fluoroscopic unit 16 may be horizontally positioned about a pivot 45 on the supporting column 18 to a position directly over or adjacent the side of the table 12, or in any intermediate position as indicated by the dotted lines 16A in Fig. 20. The fluoroscopic unit 16 may also be provided with a magnetically susceptible armature 46 adjacent a magnet 47 on the supporting column 18, so that when the fluoroscopic unit 16 is positioned over the table in working relation, it may be magnetically locked and retained in that position by virtue of the electro-magnetic lock. A suitable energizing circuit for the electro-magnetic lock, including a push-button control 48, is shown in Fig. 23.

The fluoroscopic unit 16 may also be mounted on a pivot 49 for vertical pivotal movement with relation to the supporting column 18 as shown in Fig. 24. The dotted lines 16B represent the parked or non-working position of the fluoroscopic unit 16. Referring to Fig. 25, two magnetically susceptible armatures 51 and 52 are shown positioned on one side of the vertical pivot 49 in spaced relation on the fluoroscopic unit carriage 50 and extending over a pair of aligned magnets 53 and 54 on the fluoroscope unit respectively. Thus, when the fluoroscopic unit 16 is horizontally positioned over the table 12, the magnets 53 and 54 coat with the corresponding armatures 51 and 52 respectively to lock the fluoroscopic unit in this horizontal position. The force required to separate the horizontal magnetic locks is in the order of approximately 90 lbs. each, and two of such electro-magnetic locks are sufficient to overcome the resistance of a patient lying on the table and pushing up against the fluoroscopic unit 16. Another magnet 55 is mounted on the fluoroscope unit 16 on the other side of the pivot 49 to cooperate with an armature 56 carried on the carriage 50 to lock the fluoroscope unit in the extended vertical position indicated by the dotted lines 16B in Fig. 24. A simple energizing circuit having push-button control with momentary contacts may be utilized to deenergize the electro-magnetic locks in either the horizontal or vertical positions.

In fluoroscopic spot film examinations, and particularly in the study of the stomach, the barium meal must be forced into position and held there during exposure. This is usually done by mounting a cone 43 in the form of a hemisphere in the path of the central X-ray beam and applying pressure to the patient while at the same time palpitating the stomach to be sure that the radio opaque media will flow as desired and then holding the desired position by means of a compression cone. Accordingly, the fluoroscope unit 16 must be pressed forward against the patient and locked with compression during exposure to the spot film. The electro-magnetic lock principle may likewise be adopted to accomplish this type of action in accordance with the arrangement shown in Figs. 28, 29, and 30, where the fluoroscopic carriage 50 is mounted for vertical movement along the supporting column 18 on anti-friction rollers 51. The carriage 50 is provided with one or more magnets 60 which are adapted to cooperate in magnetic locking relation with a vertical magnetically susceptible track 61 carried along the supporting column 18

throughout the desired distance of vertical movement of the carriage 50. The electro-magnetic locks 68 may be energized by means of the conveniently located switch 62, to arrest the movement of the carriage 50 and fluoroscopic unit 16 in either direction. In this way, compression may be applied to the patient and maintained during a spot film fluoroscopic examination.

Inasmuch as the carriage 50 and fluoroscopic unit 16 are adapted for vertical movement along the supporting column 18, a counter-weight arrangement which is similar to that described in relation to Fig. 15 is provided as shown in Figs. 28 and 29. The counter-weight 65 is connected to the carriage 50 through cables 66 which are looped over pulleys 67 on top of the supporting column 18 to counter-balance the carriage movement.

The electro-magnetic lock control circuits in Fig. 17 or 18 may easily be adapted to include control of the electro-magnetic compression locks 68 of Fig. 30 as shown in the control circuit arrangement of Fig. 19. The control resulting from operation of this circuit is such that when the switch 30 is in the lower position, the longitudinal electro-magnetic lock 23 instantaneously arrests that movement of the supporting column 18 while neither the crosswise electro-magnetic lock 24 nor the compression locks 60 are energized until the supporting column is centrally positioned crosswise with respect to the table 12. With the switch in the upper position, all of the electro-magnetic locks are immediately energized regardless of the position of the controlled members.

As previously noted, an auxiliary X-ray tube stand may be utilized when employing the apparatus illustrated in the drawings for the technique of radiography. One embodiment of such a tube stand is illustrated in Fig. 31 in the form of a vertical stand 70 positioned for movement along a track 71 which runs parallel to the table 12 and guided at the top by a trolley 72. In some instances, the tube stand 70 may be suspended from the trolley 72 without utilizing the track 71 at the base. An auxiliary X-ray tube carriage 73 is shown mounted for vertical movement on the tube stand 70 and is counter-balanced thereon by means of a counter-weight arrangement shown in dotted lines as embodying the counter-weight 74 with a cable 75 and pulley 76. An X-ray tube supporting arm 77 is mounted for rotation about a horizontal axis on the carriage 73 and carries an X-ray tube 78 which may be positioned along the supporting arm in accordance with the condition to be exposed.

The electro-magnetic lock principle is likewise adaptable to the various movements of the tube stand 70 and to the movements of each of the associated members relative to each other and the stand. Thus, as illustrated in Fig. 32, the tube stand 70 may be guided along the track 71 by means of a carriage 79 which is supported by rollers or wheels 80. One or both of the rollers 80 may be made of or provided with a magnetically susceptible material which will have magnetic locking attraction with a magnet 81 mounted on the carriage 79 adjacent the magnetically susceptible carriage roller 80.

The tube stand 70 is mounted for rotation about a vertical axis on the carriage 79, and the mounting to the carriage is made through an electro-magnetic lock arrangement as illustrated in Fig. 33. In the preferred embodiment shown, the carriage 79 has a flat circular journal plate 75

82 at the top adjacent the junction of the tube stand 70 with the carriage. A corresponding flange or flat journal plate 83 is carried at the base of the tube stand 70 adjacent to and in aligned relation with the disc 82 on the carriage. The tube stand flange 83 carries a magnet 84 which upon energization magnetically locks with the disc plate 82 acting as an armature on the carriage 79 in any position of the tube stand 10 relative to the carriage. Rotation of the tube stand 70 is limited by the stop 93 on the upper journal plate 83. Suitable remote controls and energizing circuits may be provided for the electro-magnetic locks 81 and 84 to effect individual or combined action in order to arrest movement of the carriage 79 or the tube stand 70 as desired.

The carriage 73 on the tube stand 70 is also provided with an electro-magnetic lock 85, as shown in the dotted lines in Figs. 31 and 34, to arrest vertical movement of the carriage relative to the stand. The cooperating armature for the magnet 85 may, in its preferred form, embody a magnetically susceptible vertical track 86 carried along the tube stand 70 adjacent the magnetic lock 85. Suitable anti-friction rollers 87 are provided by the carriage 73 to aid vertical motion of the carriage along the stand 70.

The end of the X-ray supporting arm 77, which 30 is adjacent the tube stand 70, carries a flat disc-type coupling and armature 88 which cooperates with the magnet 89 on the carriage 73. The disc armature 88 serves a dual purpose as an armature for the electro-magnetic lock 89 and as an 35 indicating dial having markings 91 on the periphery which cooperate with a stationary pointer 90 on the carriage 73 to give a visual indication of the angular displacement of the X-ray tube 78 from the initial position represented by the 40 pointer 90, as best shown in Fig. 35. An energizing circuit for the electro-magnetic locks, including remote control means, may be incorporated into the apparatus to operate the locks individually, or in combination, to arrest separate 45 or combined movements of the individual members of the apparatus.

As previously noted, it is at times desirable and necessary to transfer the center of pathology to the radiographic tube 78 in order to effect a bucky radiograph of the particular pathology under observation. The combined operation of the fluoroscopic spot film and the bucky has been described in connection with Figs. 17 and 18, and the detailed construction of the bucky mechanism in the apparatus will hereinafter be more fully set forth in connection with Figs. 36 through 40.

Fig. 36 illustrates an assembly of the X-ray apparatus with the bucky carriage 100 and film cassette carrier 101 centrally positioned within the table 12 in operating relation with the auxiliary or radiographic tube stand. The dotted lines, 18B illustrate the manner in which the fluoroscope supporting column 18 may be displaced from the region of radiographic operation by merely sliding the carriage 19 along the longitudinal track 13 and energizing the corresponding electro-magnetic lock to arrest the supporting column in an out-of-the-way position relative to the work area during a radiographic operation. The bucky carriage 100 is mounted on anti-friction rollers 102 which are adapted to traverse the longitudinal track 13 of the table.

The carriage 100 supports the film cassette carrier or tray 101 which is loosely carried there-

in for movement crosswise of the table 12 as shown in Figs. 37 and 38 where the extended crosswise position of the film tray is shown in dotted lines as 101A. The bucky carriage 100 also supports a bucky screen or diaphragm 103 which is resiliently mounted at the top of the carriage so that either an artificial or normal vibration of the apparatus will vibrate the bucky screen to effect its function in a manner well known in the art. The bucky carriage 100 may be moved throughout the length of the table by towing the handle 104 extending from the film tray 101 and urging the entire carriage in either direction along the table 12 as desired.

As previously noted in connection with Figs. 17 and 18, the positioning and centering of the bucky apparatus is a precise operation and once the setting is made and the tube stand 70 is locked in place, it is desirable to lock the bucky carriage 100 in place to prevent inadvertent or unintentional misalignment which would require a readjustment of all the essential working members involved in the radiographic technique. Accordingly, the bucky carriage 100 is also provided with a magnet 105 which cooperates with the magnetically susceptible track 13 on the table 12. Although the energizing circuit for this electro-magnetic lock may be remotely controlled after the manner of several other electro-magnetic locks in the apparatus, the preferred embodiment shown in Figs. 37 and 39 illustrates an automatic type control in the form of a spring operated switch 106 which is mounted on the bucky carriage 100 so that a spring arm 107 extends in abutting relation with one end of the film tray 101 when the tray is in the extreme enclosed position within the carriage 100. Once the bucky carriage is properly centered and positioned on the table relative to the radiographic tube 18 and a film cassette is inserted in the tray, the tray may be returned to its enclosed position within the carriage 100 so that the end which abuts the spring arm 107 of the switch 106 depresses the spring arm downward and closes the energizing circuit illustrated in Fig. 40, to lock the electro-magnetic lock 105 to the track 13 of the table, thereby arresting further movement of the carriage 100 relative to the table 12 and preventing inadvertent misalignment during the radiographic operation. By using this type of automatic control for the electro-magnetic lock 105, the bucky carriage is always locked when the film tray 101 is in the radiographic position, but the moment the tray is withdrawn enough to clear the switch arm 107, the bucky carriage is unlocked and can be moved relative to the table by urging or towing the handle 104.

The electro-magnetic lock and its application to an X-ray apparatus in accordance with this invention, as illustrated by way of example in the accompanying drawings and description, provides many distinct advantages over known types of X-ray apparatus by reason of providing conveniently located remote controls and eliminating the disadvantages inherent in the various adjustments and maintenance required for known types of mechanical locks. The fact that the electro-magnetic type lock may be electrically controlled also provides an unlimited variety of individual and combined operating characteristics for arresting individual and combined movements of a plurality of movable members relative to each other and to associated stationary members in any form of X-ray apparatus. Reference is made to our co-pending application Serial No.

205,088, filed January 9, 1951, entitled X-ray Apparatus and Control and relating to similar subject matter.

We have shown and described what we consider the preferred embodiment of our invention along with suggested modified forms, and it will be obvious to those skilled in the art that other changes and modifications, particularly with respect to the construction of the electro-magnetic lock and its application to various forms of X-ray apparatus, may be made without departing from the scope of our invention as defined by the appended claims.

We claim:

1. In an X-ray apparatus having a plurality of stationary structures, and a plurality of other corresponding structures movable relative thereto, each of said stationary structures having a magnetically susceptible member adjacent the desired positions of said corresponding movable structures respectively, a magnet having an energizing coil carried by each of said movable structures, and electrical means for automatically energizing each of said magnet coils individually or in combination, whereby said magnet is attracted and adheres to a corresponding magnetically susceptible member to arrest further movement of said respective movable structures relative to the corresponding stationary structures in predetermined relation.

2. An electro-magnetic lock comprising, a magnet having a central core and an energizing coil on said core, said magnet being hexagonal in cross section and having annular grooves spaced along the hexagonal corners respectively, a support having a cooperating hexagonal opening for said magnet, magnet mounting means including annular resilient members adapted to encircle said magnet, each of said annular members being seated in said annular grooves on the magnet and disposed in spaced relation on either side of said support, a magnetically susceptible armature and a support therefor, means effecting relative motion between said magnet and armature supports, electrical means for energizing said coil when said magnet is positioned adjacent said armature to cause mutual magnetic attraction and adhesion therebetween and thereby arrest further relative motion between said supports.

3. In an electro-magnetic lock of the type described, a magnet having a core and energizing coil therefor, said magnet being hexagonal in cross section and having annular grooves spaced along the hexagonal corners thereof, a support having a cooperating hexagonal opening for said magnet, said support having a cross section in the direction of the opening of less dimension than the spacing between the annular grooves on said magnet, a pair of split annular members, each of said annular members having an inner diameter equal to the inner diameter between diametrically opposed annular grooves of said magnet, and having an outer diameter greater than the diameter of the hexagonal opening through said support, one of said split annular members being disposed within the annular grooves on the magnet on either side of said support, thereby restricting movement of said magnet relative to the support beyond the limiting positions of said annular members in a direction normal to said support, a magnetically susceptible armature and a support therefor, means effecting relative motion between said magnet and armature supports, electrical means for energizing said coil when said magnet is positioned

13

adjacent said armature to cause said magnet to be attracted and adhere to said armature and thereby arrest further relative motion between said supports.

4. An electro-magnetic lock comprising a magnet having a core and an energizing coil therefor, said magnet being hexagonal in cross section and having annular grooves spaced along the hexagonal corners thereof, a support having a cooperating hexagonal opening for said magnet, a magnetically susceptible armature and a support therefor positioned adjacent said magnet support, a pair of split annular members, each of said annular members having an inner diameter equal to the inner diameter between diametrically opposed annular grooves on said magnet and having an outer diameter greater than the diameter of the hexagonal opening in said support, each of said split annular members adapted to be seated within said spaced annular grooves on the magnet on opposite sides of said support, the spacing between the said spaced annular grooves along each hexagonal corner of said magnet being greater than the cross section of said support in the direction of said hexagonal opening, thereby allowing relative displacement between said magnet and support between said limiting annular members toward intimate contact with said armature, means effecting relative motion between said magnet and armature supports, electrical means for energizing said coil when said magnet is positioned adjacent said armature to cause said magnet to be attracted and adhere thereto and thereby arrest further relative motion between said support, and resilient insulating means surrounding said coil and covering the portion of said magnet adjacent the armature, said insulating cover coacting with said armature to increase the coefficient of friction between said magnet and armature when said magnet is energized and to urge said magnet and armature apart when said magnet is de-energized.

5. In an X-ray apparatus having a plurality of structures freely supported for movement relative to each other, a plurality of electro-magnetic locks coacting between different relatively movable structures to lock them together against displacement, each lock including a magnetically susceptible member carried by one structure and a magnet having an energizing coil carried by another structure in operative proximity to the corresponding magnetically susceptible member, means permitting displacement of each magnet for physical contact with the corresponding magnetically susceptible member in response to a magnetic attraction therebetween, and means for selectively energizing the coils to create the magnetic attraction and lock the corresponding structures together in predetermined position relative to each other.

6. In an X-ray apparatus having a stationary member and another member freely supported for longitudinal and crosswise movement relative to said stationary member, a magnetically susceptible guide disposed parallel to the longitudinal and crosswise direction of movement respectively, a pair of magnets each having an energizing coil and each carried by the movable member adjacent the longitudinal and crosswise guide respectively, means permitting displacement of each magnet toward physical contact with the corresponding guide in response to a magnetic attraction therebetween, and means for simultaneously energizing each of said ener-

14

gizing coils to create the magnetic attraction and lock the movable member in a selected longitudinal and crosswise position relative to the stationary member.

7. In an X-ray apparatus having a stationary member and another member freely supported for longitudinal and crosswise movement relative to said stationary member, a magnetically susceptible guide disposed parallel to the longitudinal and crosswise direction of movement respectively, a pair of magnets each having an energizing coil and each carried by the movable member adjacent the longitudinal and crosswise guides respectively, means permitting displacement of each magnet toward physical contact with the corresponding guide in response to a magnetic attraction therebetween, and means automatically responsive to said movable member being centrally positioned in the crosswise direction to simultaneously energize each of said energizing coils and create the magnetic attraction to lock the movable member in a selected longitudinal and crosswise position relative to the stationary member.

8. The apparatus of claim 7 wherein the means for energizing the coils includes an energizing circuit having a normally open switch adapted to be closed by the movable member when the latter is positioned centrally in a crosswise direction relative to the stationary member.

9. In an X-ray apparatus having a stationary member and another member freely supported for longitudinal and crosswise movement relative to a stationary member, a magnetically susceptible guide disposed parallel to the longitudinal and crosswise direction of movement respectively, a pair of magnets each having an energizing coil carried by the movable member adjacent the longitudinal and crosswise guide respectively, means permitting displacement of each magnet toward physical contact with corresponding guide in response to a magnetic attraction therebetween, an electrical energizing circuit for energizing the coils to create the magnetic attraction and lock the movable member in a selected longitudinal and crosswise position relative to the stationary member, a plural position switch in said energizing circuit, said switch in one position connecting each of the coils in the circuit and in another position connecting only the coil adjacent the longitudinal guide in the circuit, and means cooperating with the switch in the latter position in response to said movable member being centrally positioned crosswise relative to the stationary member to automatically connect the coil adjacent the crosswise guide in the energizing circuit.

10. In an X-ray apparatus having a stationary member and a plurality of other members freely supported for movement relative to each other and to the stationary member, one of said movable members being mounted for longitudinal and crosswise movement relative to the stationary member, another of said movable members being mounted for vertical motion along said first movable member, a magnetically susceptible guide disposed parallel to the longitudinal and crosswise directions of movement respectively of the first movable member, another magnetically susceptible guide disposed parallel to the vertical motion of said other movable member, a plurality of magnets each having an energizing coil and each operably disposed on a member for coaction with the guide corresponding to the direction of relative movement of said member,

means permitting displacement of each magnet for physical contact with the corresponding guide in response to a magnetic attraction therebetween, and electrical means for selectively energizing each of the magnet coils to create the magnetic attraction and lock the corresponding movable members in selected longitudinal, crosswise and vertical positions respectively.

11. In an X-ray apparatus having a stationary member and a plurality of other members freely supported for movement relative to each other and to the stationary member, one of said movable members being mounted for longitudinal and crosswise motion relative to the stationary member, a second movable member mounted for vertical motion along said first movable member, a third movable member mounted for pivotal horizontal and vertical positioning relative to said second movable member, a first magnetically susceptible guide operably disposed between the stationary member and the first movable member and parallel to the longitudinal and crosswise relative motions between said members, a second magnetically susceptible guide disposed between the second and first movable member and parallel with the vertical relative motion therebetween, a third magnetically susceptible guide operable disposed between the second and third movable members in a horizontal and vertical plane respectively, a plurality of magnets each having an energizing coil and each operably disposed on a corresponding member for coaction with the magnetically susceptible guide corresponding to the direction relative of movement between the corresponding members, means permitting displacement of each magnet toward physical contact with the corresponding guide in response to a magnetic attraction therebetween, and electrical means for selectively energizing each of the magnet coils to create the magnetic attraction and to lock the corresponding movable member in a selected position in predetermined relation to each of the other members.

12. In an X-ray apparatus having a stationary member and a plurality of other members freely supported for movement relative to each other and the stationary member, a first movable member mounted for longitudinal and crosswise motion relative to the stationary member, another movable member mounted for vertical motion along the first movable member, a magnetically susceptible guide disposed between the first movable member and the stationary member and parallel to the longitudinal and crosswise direction of relative movements, a second magnetically susceptible guide disposed between said other movable member and the first movable member and parallel to the vertical direction of relative movement, a plurality of magnets each having an energizing coil and each operably disposed on a member adjacent a guide corresponding to the direction of relative movement between the corresponding members, means permitting displacement of each magnet toward physical contact with the corresponding guide in response to a magnetic attraction therebetween, an electrical energizing circuit for each of the magnet coils, a switch for connecting the magnet coil adjacent the longitudinally disposed guide in the energizing circuit to lock the first movable member in a selected longitudinal position relative to the stationary member, and means automatically responsive to the central positioning of the first movable member in a crosswise direction relative to the stationary member and coacting with the

switch in the energizing circuit to selectively energize each of the other magnet coils and thereby automatically lock the first movable member in central position in the crosswise direction and lock the other movable member in a predetermined vertical position.

13. In an X-ray apparatus having a stationary member and plurality of other members freely supported for movement relative to each other and to the stationary member, a first movable member mounted for longitudinal and crosswise motion relative to the stationary member, another movable member mounted for vertical motion along said first movable member, a magnetically susceptible guide disposed between the first movable member and stationary member and parallel to the longitudinal and crosswise directions of relative movement, a second magnetically susceptible guide disposed between said other movable member and the first movable member and parallel with the vertical relative movement, a plurality of magnets each having an energizing coil and each disposed on a relatively movable member adjacent the guide corresponding to the relative direction of movement of said member, means permitting displacement of each magnet toward physical contact with the corresponding guide in response to a magnetic attraction therebetween, an electrical energizing circuit for the magnet coils, a plural-position switch in said energizing circuit, said switch coacting in one position on the circuit to simultaneously energize all of the magnet coils and thereby lock each of the relatively movable members in selected positions along their direction of relative movement and in predetermined relation to each other, said switch coacting in the circuit in another position to energize only the magnet coil corresponding to the longitudinal guide to lock the first movable member in a predetermined longitudinal position, and means coacting with the switch in the latter position to automatically energize the other magnet coils consequent upon the first movable member being centrally positioned in a crosswise direction relative to the stationary member, thereby locking the first movable member in central position in a crosswise direction and locking the second movable member in a predetermined vertical position.

14. An electro-magnetic lock comprising a magnet having an outer core portion enclosing an inner core portion and spaced therefrom by a recess extending inwardly from one face of the magnet, an energizing coil disposed in the recess about the inner core portion, a support for said magnet, a magnetically susceptible armature and a support therefor, means effecting relative motion between the magnet and the armature support, electrical means for selectively energizing said coil when the magnet is positioned adjacent the armature to cause mutual magnetic attraction therebetween and thereby arrest further relative motion between the supports, and elastic material for insulating the coil in the recess, said material projecting outwardly from the recess beyond said one magnet face for frictional coaction with said armature when energized and for resilient coaction with said armature to urge the magnet away when deenergized.

15. An electromagnetic lock comprising, a magnet having an outer core portion enclosing an inner core portion and spaced therefrom by a recess extending inwardly from one face of the magnet, an energizing coil disposed in the recess

about the central core portion, a support for said magnet, means for mounting the magnet to prevent relative motion between said magnet and magnet support in the plane of the support, a magnetically susceptible armature and support therefor, means for effecting relative motion between the magnet and armature supports, electrical means for selectively energizing the coil when said magnet is positioned adjacent the armature to cause mutual magnetic attraction therebetween and thereby to arrest further relative motion between the supports, an elastic insulating material enclosing the coil in the recess and projecting outwardly from the recess and beyond said one magnet face for coaction with said armature adapted to aid the magnet arresting action when energized and to resiliently urge the magnet away from the armature when deenergized.

16. An electromagnetic lock comprising, a hexagonally shaped magnet having an outer core portion enclosing an inner core portion and spaced therefrom by an annular recess extending inwardly from one face of the magnet, an energizing coil disposed in the recess about the central core portion, a support having a cooperating hexagonal opening for holding the magnet against rotation therein, means for maintaining axial alignment of the magnet in the support opening, a magnetically susceptible armature and a support therefor, means for effecting relative motion between the magnet and armature supports, electrical means for selectively energizing the coil when said magnet is positioned adjacent the armature to cause mutual magnetic attraction therebetween and thereby arrest further relative motion between the supports, an elastic insulating material enclosing the coil in the recess and projecting outwardly from the recess and beyond said one magnet face for coaction with the armature adapted to aid the magnet arresting action when energized and to urge the magnet away from the armature when deenergized.

17. An electromagnetic lock comprising a magnet having an outer core portion substantially enclosing an inner core portion and spaced therefrom by a recess extending inwardly from one face of the magnet, an energizing coil disposed in the recess about the inner core portion, a magnetically susceptible armature, means for supporting the magnet and armature in spaced relation for relative movement, means for energizing the coil to cause magnetic attraction and coaction between the magnet and armature, and elastic material for insulating the coil in the recess and projecting outwardly beyond said one magnet face for coaction with said armature adapted to aid the magnetic coaction when the magnet is energized and to aid the release of the magnet from such coaction when deenergized.

18. An electromagnetic lock comprising a magnet having an energizing coil thereon, a magnetically susceptible armature, means for supporting the magnet and armature in spaced relation and for displacement towards and away from physical contact with each other in response to a magnetic attraction therebetween, means for connecting the magnet coil to a source

of electrical energy to create the magnetic attraction and lock the magnet and armature together, and electrical insulation between the magnet and the coil projecting into the space between the magnet and armature, said insulation being elastic and having a greater coefficient of friction with the armature than the magnet and adapted to increase the locking action therebetween when the magnet is energized and to aid the release of the magnet from the armature when deenergized.

19. In an X-ray apparatus having a pair of structures mounted for movement relative to each other and adapted to be positioned in predetermined relation to each other for cooperative performance to produce a selected unitary result, a magnetically susceptible member carried by one structure and a magnet having an energizing coil carried by the other structure in operative proximity to the member, means coacting between the magnet and member to permit displacement towards physical contact with each other in response to a magnetic attraction therebetween, and means for selectively energizing the magnet coil to create the magnetic attraction between the magnet and member and lock them together against relative movement when they are positioned into the said predetermined relation to each other.

20. An X-ray apparatus having a stationary structure and another structure movable relative thereto and adapted to be moved into a predetermined position for cooperative performance with the stationary structure to produce a selected unitary result, a magnetically susceptible member carried by the stationary structure and a magnet having an energizing coil carried by the movable structure in operative proximity to the magnetically susceptible member, means coacting between the magnet and the magnetically susceptible member to permit displacement toward physical contact with each other in response to a magnetic attraction therebetween, and means for selectively energizing the magnet coil to create a magnetic attraction between the magnet and the magnetically susceptible member and lock them together against relative movement when the movable structure is moved into the said predetermined position.
